UNITED STATES PATENT OFFICE.

THOMAS B. JACKSON, OF BELMONT, OHIO.

FIRE-PLACE HEATER.

SPECIFICATION forming part of Letters Patent No. 427,767, dated May 13, 1890.

Application filed September 26, 1889. Serial No. 325,110. (No model.)

To all whom it may concern:

Be it known that I, THOMAS B. JACKSON, a citizen of the United States, residing at Belmont, in the county of Belmont and State of Ohio, have invented certain new and useful Improvements in Fire-Place Heaters; and I do declare the following to be a full, clear, and exact description of the invention, such as will enable others skilled in the art to which it appertains to make and use the same, reference being had to the accompanying drawings, and to the letters of reference marked thereon, which form a part of this specification.

This invention relates to fire-place heaters which heat by direct radiation and by hot air.

The object of the invention is to increase the heating surface and capacity of the hot-air chambers, whereby the fuel is used to the best possible advantage.

The improvement consists of the novel features and the peculiar construction and combination of the parts, which will be herein-after more fully described and claimed, and which are shown in the accompanying drawings, in which—

Figure 1 is a front view of a fire-place heater embodying my invention. Fig. 2 is a cross-section on the line Y Y of Fig. 1. Fig. 3 is a longitudinal section on the line X X of Fig. 2.

The fire-place comprises two side hot-air chambers A A, one on each side of the fire-grate B, a rear hot-air compartment C, and the two horizontal hot-air boxes D and E, the hot-air box E communicating in the rear with the compartment C and at its ends with the chambers A A through openings a in the inner side walls of said chambers, and the box D communicating at its ends with the chambers A through openings b in the said inner side walls of chambers A. The hot-air box E projects over the fire-grate B, terminating short of the plane of the front plate F to leave a vertical passage f for the escape of smoke and gases. The box D is placed directly above the box E and extends from the front plate to within a short distance of the back plate G, leaving a smoke-passage g in the rear thereof. The box D is placed above box E

sufficiently far to form the smoke-flue h between them. A register H is placed in the front of box D for the escape of hot air into the room.

The heater may be used for heating adjoining rooms or rooms above by connecting suitable conducting-pipes with the hot-air chambers thereof, the pipes connecting at convenient points, as at I.

The operation of the heater is as follows: Cold air enters the compartment C through pipe or pipes J, passing from the same into box E, and from box E into the chambers A A through opening a, and from said chambers A A into box D through opening b, and from box D into room through register H. The smoke and gases pass upward from grate B through passage f, flue h, and passage g into chimney. (Not shown.)

Having fully described my invention, what I claim, and desire to secure by Letters Patent, is—

1. A fire-place heater comprising side hot-air chambers, a rear hot-air compartment, and horizontal hot-air boxes D and E, arranged above the fire-grate and communicating with the hot-air chambers and having a smoke-flue between them, the hot-air box D having a register in its front, substantially as described.

2. The combination, with the hot-air chambers A A, having the fire-grate arranged between them, and the hot-air compartment C in the rear of the grate, of the two horizontal hot-air boxes D and E between the hot-air chambers and communicating therewith at their ends through openings b and a, respectively, the box E opening into compartment C and arranged directly over the fire-grate, and the box D having register H and placed above the smoke-flue h, substantially as and for the purpose described.

In testimony whereof I affix my signature in presence of two witnesses.

THOMAS B. JACKSON.
